UNITED STATES PATENT OFFICE.

HUIBERT CORNELIS GHIJSEN, OF MIDDELBURG, NETHERLANDS, ASSIGNOR TO N. V.
THE VITRITE WORKS, OF MIDDELBURG, NETHERLANDS, A LIMITED LIABILITY
COMPANY, OF THE NETHERLANDS.

APPARATUS FOR THE MANUFACTURING AND ADJUSTMENT OF CONTACT-PLATES IN SWAN LAMP-BASES.

1,331,755.

Specification of Letters Patent. Patented Feb. 24, 1920.

Application filed April 18, 1919. Serial No. 291,154.

To all whom it may concern:

Be it known that I, HUIBERT CORNELIS GHIJSEN, a subject of the Queen of the Netherlands, residing at Middelburg, Province of 5 Zealand, in the Kingdom of the Netherlands, have invented certain new and useful Improvements in Apparatus for the Manufacturing and Adjustment of Contact-Plates in Swan Lamp-Bases, of which the following is a specification.

10 This invention relates to an apparatus for the manufacturing and adjustment of contact plates in Swan lamp bases. For this purpose the two contact plates for one lamp base are placed in a plunger head as one twin 15 plate and in this plunger head are separated one from the other by the strip connecting the two plates being parted in the middle: the portion of the strip left over on each plate is then bent up in the operation 20 of placing the plates on the pins in the mold in which the lamp base is pressed after which in the following phase of the operation the case is placed in the mold and the insulating mass poured in.

25 The apparatus for carrying out this method according to this invention is characterized by a guide channel for guiding the plates into the vertical guide opening of a plunger head movable in a vertical direction. This opening has a section corresponding 30 to the shape of the twin contact plates. At the lower end of the opening there is a small anvil with beveled surfaces on its lower edges and in the plunger head there 35 is a spring pressed core piece with a forked shaped lower end. The fork legs glide on both sides over the small anvil, and, after the connecting strip has been cut through press down the two contact plates, bend up 40 the portions of the strip remaining and place the contact plates on the pins provided for them in the mold, the pins entering into holes formed for them in the lower ends of the fork legs.

45 An important simplification in the method of production and adjustment of the contact plates is made whereby the dividing of each twin plate into two halves is carried out by tearing the connecting strip which for this purpose is weakened at or near the middle.

50 The invention relates also to an apparatus

for the application of the second method above mentioned, characterized by the fact that the core piece movable in the plunger 55 head is not provided with a chisel or other cutting tool for dividing the contact plates and that the small anvil in the plunger head is formed in the middle of its upper surface with a slit for receiving the connecting strip 60 of the twin contact plate.

The invention is illustrated on the accompanying drawings.

Figure 1 is a longitudinal section through a plunger head with mold.

Fig. 2 is likewise a longitudinal section of the lower portion of the plunger head taken in a plane at right angles to that of Fig. 1 with the movable core omitted.

Fig. 3 is a cross section of the plunger 70 head corresponding to the line A—A of Fig. 2.

Fig. 4 is a cross section corresponding to the line B—B of Fig. 2.

Fig. 5 is a cross section corresponding to 75 the line C—C of Fig. 2.

Fig. 6 shows in side elevation the core piece with forked ends.

Fig. 7 is an end view of the forked end 80 of the core piece.

Fig. 8 is a plan view of the contact plates before they are inserted to the plunger head.

Fig. 9 is a plan view of the contact plates after they emerge from the plunger head.

Fig. 10 is an elevation of the parts shown 85 in Fig. 9.

The twin contact plates are fed into a plunger head 11 through a guide channel 15 in the holder arm 7 by means of a feeding bar 6 having a reciprocating motion. The plunger head is formed with a side opening 13 for the insertion of the contact plates. The plunger 10 is open on two opposite sides and at its upper end is screwed fast into a spring box 51 inclosing a spring 21 which 95 at its upper end presses against a collar 22 of the core piece 20.

The core piece has at its lower end a two legged fork 24. The spring 21 thus holds the core piece and fork continually pressed 100 upwardly. The core piece 20 with fork 24 has a common axis with the plunger and can move along this axis against the pressure of the spring. The two fork legs 25 the sec-

tion of which corresponds with the shape of the contact plates work through guide openings in the conical head 12 of the plunger head these openings having sections corresponding to that of the fork legs. In the lower end of the plunger head there is a small anvil 30 attached by screws 52 and this anvil partially closes the opening in the plunger head. With the downward motion 10 of the fork 24, 25 the fork legs glide on both sides over the anvil. The plunger head is guided in its motion by the bore 9 in the guide box 8.

A mold 16 is placed under the guide box 8 and in the opening 17 in this mold is placed 15 the metal case for the lamp base and insulating mass. Two pins 18 are fixed to the base 19 of this mold on which the contact plates can be placed. The contact plates 20 are formed with holes for this purpose. The small anvil 30 is formed on its upper side with a transverse slit or groove 53 in which the connecting strip rests when the twin contact plate is inserted. This slit insures 25 the plate being in the correct position before the plunger starts on its downward stroke.

In the opening 13 for the insertion of the twin contact plate in the plunger head there 30 are guide plates 54 which are screwed on both sides to the inner wall of the plunger head. On inserting the contact plates the pointed outer ends of these contact plates 35 glide along the guide plates until the contact plates reach the middle of the plunger head in which position the strip is above the slit 53. The contact plate then falls down until the connecting strip rests in the slit in the small anvil.

40 The guide box 8 is provided at the side where the contact plates are inserted with an inwardly projecting portion 55 in order to insure the passage of the contact plates from the guide channel 15 into the plunger head.

45 The apparatus works as follows:

The twin contact plate is inserted through the guide channel of the apparatus and through the opening 13 in the lowest portion 50 of the plunger head. The plate then lies on the anvil 30 and rests with the strip connecting together the two halves of the contact plate in the slit 53 in the middle of the anvil.

55 On the downward stroke of the plunger the plunger head with the anvil 30 descends to the bottom of the mold the twin contact plate being taken down with it. The holes with which the two halves of the contact 60 plate are provided are thus brought over the pins fixed in the bottom of the mold and

the pins thrust through them. The pins are pointed for this purpose.

When the plunger 10, 12 comes to rest on the bottom of the mold the core piece 20, 24 65 still continues its motion downward and the spiral spring 21 situated in the spring box 51 is thereby compressed.

Two vertical holes are bored in the bases of the fork legs in positions corresponding 70 to the positions of the two pointed pins in the mold.

The fork legs thus move over the mold pins on the downward motion and cause the contact plate to be held.

As the two legged plunger 24 goes farther downward the connecting strip tears apart at the thinnest place and the two halves of the strip are bent up against the anvil or bridge piece. The two contact plates are 80 thus placed in their correct positions on the bottom of the mold.

After this first the core piece 24, 25 and then the plunger 10, 12 commence their upward stroke and another twin contact plate 85 can be brought along for placing in the following mold.

What I claim is:

1. Apparatus for the manufacture and adjustment of contact plates in Swan lamp bases characterized by a guide channel for guiding the plates into the vertical guide opening of a plunger head movable in a vertical direction, this opening having a section corresponding to the shape of the twin contact plates and at the lower end of the opening there being provided a small anvil with beveled surfaces on its lower edges and the plunger head being provided with a spring pressed core piece with a fork 90 shaped lower end, the fork legs of the same slide on both sides over the small anvil and after the connecting strip has been cut through, press down the two contact plates, 95 bend up the portions of the strip left over 100 and place the contact plates on the pins provided for them in the mold, the lower ends of the fork legs having holes into which the said pins enter.

2. Apparatus according to claim 1 characterized by the fact, that the core piece movable in the plunger head is not provided 110 with a chisel or other cutting tool for dividing the contact plates and that the anvil in the plunger head is formed in the middle 115 of its upper surface with a slit for receiving the connecting strip of the twin contact plate.

In testimony whereof I have hereunto set my hand.

HUIBERT CORNELIS GHIJSEN.
